US00D652829S

(12) **United States Design Patent**
Kim et al.

(10) **Patent No.:** US D652,829 S
(45) **Date of Patent:** ** Jan. 24, 2012

(54) **COVER FOR MOBILE COMMUNICATION TERMINAL**

(75) Inventors: **Yoon-Young Kim**, Yongin-si (KR);
Jin-Soo Kim, Yongin-si (KR);
Seog-Guen Kim, Seoul (KR)

(73) Assignee: **Samsung Electronics Co., Ltd.**,
Suwon-Si (KR)

(**) Term: **14 Years**

(21) Appl. No.: **29/389,559**

(22) Filed: **Apr. 13, 2011**

(30) **Foreign Application Priority Data**

Dec. 29, 2010 (KR) 30-2010-0056521

(57) **CLAIM**

The ornamental design for a cover for mobile communication terminal, as shown and described.

DESCRIPTION

FIG. 1 is a front perspective view of a cover for mobile communication terminal;

FIG. 2 is a front view of the cover for mobile communication terminal of FIG. 1;

FIG. 3 is a rear view of the cover for mobile communication terminal of FIG. 1;

FIG. 4 is a left-side view of the cover for mobile communication terminal of FIG. 1;

FIG. 5 is a right-side view of the cover for mobile communication terminal of FIG. 1;

FIG. 6 is a top plan view of the cover for mobile communication terminal of FIG. 1;

FIG. 7 is a bottom plan view of the cover for mobile communication terminal of FIG. 1; and,

FIG. 8 is a front view of the cover for mobile communication terminal of FIG. 1 shown in an open state, with an unclaimed mobile phone communication terminal depicted in broken lines.
